(57) **CLAIM**

The ornamental design for a maternity support, as shown and described.

DESCRIPTION

FIG. 1 is a perspective view of a maternity support, showing the new design in a position of use;

FIG. 2 is an exploded top plan view thereof;

FIG. 3 is an exploded bottom plan view thereof;

FIG. 4 is a front perspective view thereof, shown in a position of use;

FIG. 5 is a rear perspective view thereof, shown in a position of use; and,

FIG. 6 is a left side perspective view thereof, shown in a position of use.

The broken lines shown in the drawings illustrate a human figure and the stitching, which are for environmental purposes only and do not form any part of the claimed design.
